UNITED STATES PATENT OFFICE

133,781

DESIGN FOR A DIVE MASK

Harold Leslie Messinger, Terminal Island, Calif.,
assignor to Sea-Net Manufacturing Co., Terminal Island, Calif.

Application January 4, 1941, Serial No. 97,802

Term of patent 14 years

To all whom it may concern:

Be it known that I, Harold Leslie Messinger, a citizen of the United States, residing at Terminal Island, in the county of Los Angeles and State of California, have invented a new, original, and ornamental Design for a Dive Mask, of which the following is a specification, reference being had to the accompanying drawing, forming part thereof.

In the aforesaid drawing:

Fig. 1 is a perspective view of a dive mask showing my new design, and

Fig. 2 is a rear elevational view thereof.

I claim:

The ornamental design for a dive mask, as shown.

HAROLD LESLIE MESSINGER.
